AMBULATORY INVALID CHAIR

Walter R. Nelson, Elmhurst, Ill.

Application September 20, 1946, Serial No. 698,105

6 Claims. (Cl. 280—266)

I

This invention relates to improvements in ambulatory chairs and in particular to that type of chair which is adapted for use by invalids to propel themselves from place to place.

Heretofore, ambulatory chairs have been provided for invalids who are totally incapacitated physically and must be pushed from place to place by an attendant. Another type of chair has been marketed for the use of persons who have the use of their arms and are able to propel themselves thereby. A third type of chair provides for steering the moving chair by movement of the occupant's body. Each of these chairs have been designed to help overcome a certain physical handicap and are consequently limited in their scope of application.

In this invention there is provided an ambulatory chair which may be used as an ordinary wheel chair under the care of an attendant, or may be propelled and steered by the occupant. Steering is accomplished by use of the occupant's feet or, if desired, by swaying his back from side to side against a backrest. Propulsion of the chair may be effected by use of the arms. Means are also provided whereby a one-armed patient may propel himself. This is a distinct advantage over the ordinary wheel chair wherein control of both wheels must be had in order to propel and steer the chair. Also, there is incorporated in this wheel chair means whereby the occupant can exercise his arms or his legs as he sits in the chair. Furthermore, in my invention I have provided new and novel apparatus for accomplishing these operations.

It is therefore an object of my invention to provide an ambulatory chair which may be propelled by the occupant by use of his arms or may be used as a conveyance under the guidance of an attendant.

It is another object of this invention to provide a chair equipped with means whereby a one-armed occupant may propel himself.

It is a further object of this invention to provide a chair wherein an occupant may steer the chair either by use of his feet or by use of his back.

Another object of this invention is to provide in a wheel chair exercising means for the occupant's arms and legs.

Another and further object of this invention is to provide means for easy adjustment of the chair for the comfort of the occupant.

It is an important object of this invention to provide means whereby the alternate methods of steering and propelling the chair may be quickly

2

changed over from one type of operation to the other.

It is another object of this invention to provide an ambulatory chair that is simple in construction and efficient in operation.

According to the general features of my invention, I have provided an ambulatory chair having a set of propelling levers which are easily accessible to the occupant by which he may propel himself in the chair without the aid of an attendant.

Another feature of this invention is the provision of a set of propelling levers on either side of the chair whereby an occupant having only one arm may propel the chair.

A further feature is the provision of a series of quick-change locks whereby the alternate methods of propelling the chair and of steering the chair may be quickly changed from one method to the other.

Another and further feature of this invention is the provision of a backrest which will, upon the occupant leaning to right or left, through a suitable linkage and drive shaft, effect the steering of the front wheels.

Another important feature of this invention is the provision of means whereby the propelling levers may be disconnected so that the occupant may use these levers for exercise of his arms.

Another feature of this invention lies in the provision of means for disconnecting the foot pedals for use by the occupant in exercising his legs.

A further feature of this invention is the provision of propelling lever arms so connected on the crankshaft in relation to each other that at least one of the levers will always be in position to propel the chair even though the other lever is on dead-center.

A still further feature of this invention is the provision of arm rests which are adaptable for adjustment in a vertical direction and removable propelling levers whereby, with the arm rests in a lowered position and the removable propelling levers removed, an invalid patient may be easily placed in the chair.

Another important feature of this invention is the provision of a rear axle to which only one of the rear wheels is secured for rotation with the axle, the other wheel floating freely on the axle, thus providing a differential action which allows the chair to be readily turned and pivoted.

Other and further important features and objects of this invention will be apparent from the

disclosures in the specifications and the accompanying drawings.

On the drawings:

Figure 1 is a side elevational view of an ambulatory chair embodying the features of this invention.

Figure 2 is a front elevational view of the ambulatory chair illustrated in Figure 1.

Figure 3 is a sectional plan view taken substantially on line III—III of Figure 1 looking in the direction indicated by the arrow.

Figure 4 is a sectional side elevation view taken substantially on line IV—IV of Figure 3.

Figure 5 is a fragmentary sectional end view taken on line V—V of Figure 1.

Figure 6 is a fragmentary sectional side view taken on line VI—VI of Figure 2.

Figure 7 is a fragmentary sectional rear elevation taken on line VII—VII of Figure 4.

Figure 8 is an enlarged fragmentary sectional view taken on line VIII—VIII of Figure 7.

Figure 9 is a fragmentary sectional rear elevation view taken on line XI—XI of Figure 4.

Figure 10 is an enlarged fragmentary sectional side elevation taken on line X—X of Figure 2.

In the embodiment of my invention illustrated in Figures 1 and 2 there is shown an ambulatory chair comprising a chassis 10 on which is mounted a seat assembly 55 and a back supporting assembly 80.

The chassis assembly 10 includes a framework comprising side structural members 11 and 11a, one at either side of the chair, connected together by three cross members 12a, 12b and 12c. These frame members are secured together as by welding. A rear handle member 13 is rigidly secured to this framework and is disposed upwardly from the rear end thereof. The chassis 10 is supported at its rear end on wheels 14 and 14a which are disposed on an axle 15. The wheel 14 is keyed for rotation with the axle 15 while the wheel 14a is mounted for free floating action on the axle. Two vertical support members 16 and 16a and two slanted support members 17 and 17a secured as by welding to the frame members 11 and 11a and disposed at their lower ends about the axle 15 support the frame in spaced relation to the axle.

At its front end the chassis assembly 10 is supported by a steerable front wheel assembly 20 being connected thereto by a support member 19. The support member 19 is rigidly secured to the cross member 12b at the center thereof by means of a V shaped support member 19a (Fig. 4) comprising two metal straps secured at the apex of the V to the structural member 19 and at their open ends to the cross member 12b. A tubular member 19b welded to cross member 12a is secured to support member 19 by a strap 19c. The opening in the tubular member and the opening in the V shaped support 19a provide a passage-way for a driveshaft the operation of which will be disclosed hereinafter. Support member 19 is essentially a four-sided structure having an opening in the center and cross braces 19d and 19e connecting the opposite sides.

At its front end the support member 19 is rigidly secured to a bearing cover 43 of the front wheel assembly 20. The wheel assembly 20 comprises a pair of wheels 21 and 21a disposed for rotation on an axle 22. A yoke member 23 is pivotally mounted on the axle 22 and securely attached, as by press fit, to a vertical steering shaft 24 which is keyed to a bevel gear 25. As best seen in Figure 6, a member 26, having two tubular bushing portions 26a and 26b disposed at

right angles to each other, is adapted to fit inside the yoke 23 and to journal a pivot pin 27 in portion 26a and the axle 22 in portion 26b. The pivot pin 27 is also journaled in opposite sides of the yoke 23. Thus the wheels 21 and 21a are mounted for pivoting action about pin 27 as shown in Figure 2. This arrangement affords a knee action effect whenever one wheel passes over a bump or slight obstruction. As further illustrated in Figure 6, the axle 22 is disposed rearwardly from the center line of the vertical shaft 24 about whose axis the front wheels are adapted to pivot. This provision for off-set pivoting permits easy steering of the wheels.

Referring to Figure 10, it may be seen that the vertical shaft 24 is freely disposed in a cylindrical housing 28 being rotatably mounted on a ball bearing assembly 29 which is held in a recess 28a of the housing 28. A shaft collar 30, secured to the shaft 24 just above the upper end of the yoke 23, acts at a lower guide surface for the ball bearing assembly 29.

I have provided means for locking the shaft 24 to the housing 28 in the form of a quick-change lock assembly 31. This lock assembly, which is adapted to be positioned in an outwardly extending cylindrical boss 28b of the housing 28, comprises a plunger 32 having two sets of pins 33 and 34 projecting outwardly from its surface. These pins 33 and 34 are disposed normal to the axis of the plunger in spaced relation to each other, the pin 33 being displaced approximately 90° further around the plunger 32 than the pin 34. An adapter sleeve 36 having two slots 36a disposed 180° apart is adapted to slide over plunger 32. A coil spring 37 also fits over the plunger 32.

In assembling the lock 31, the pin 34 is first pressed into the plunger 32. The adapter sleeve 36 is then positioned on the plunger with the pin 34 in the slot 36a. Next, the spring 37 is inserted around the plunger abutting the adapter sleeve 36 and then the pin 33 is pressed into place on the plunger 32. The assembled lock is then positioned in the boss 28b and locked therein by any suitable means, such as, by a setscrew 38 which is adapted to screw into threaded holes in the boss 28b and in the sleeve 36.

With the lock thus assembled, the plunger 32 will extend slightly into an opening 24a in the vertical shaft 24. The shaft will then be locked to the housing 28. To release the shaft 24 from the housing 28, the plunger 32 is retracted from the opening 24a by means of a knob 39 attached to the end of the plunger. As the plunger is retracted from the opening 24a, the pin 34 will move out of the slot 36a and the pin 33 will compress the spring 37. When the pin 34 is completely out of the slot 36a the plunger is rotated 90° and then released. The pin 34 will then be held on a ledge 36b of the adapter sleeve 36 due to the action of the coil spring 37. The amount that the plunger 32 extends into the opening 24a when the shaft 24 is locked to the housing 28 will always be less than the length of the slot 36a in order that when the pin 34 is pulled out of the slot 36a the plunger 32 will be entirely retracted from the opening 24a. Thus the shaft 24 will be released from the housing 28.

In order that the housing 28 be capable of either being locked to the frame of the chair or of pivoting in the frame, I have provided a threaded portion 28c at the upper end of the housing 28. A lower retainer member 40 is screwed into place on the housing 28 and locked thereon by a locknut 41. A ball bearing assembly

42 is adapted to be positioned in a recess 40a of the member 40. The outer bearing housing 43, which, as previously mentioned, is rigidly secured to the support member 19 of the chassis of the chair, is positioned over the bearing 42 on a bearing recess 43a resting on the outer race of the bearing.

The outer race of an upper ball bearing 44 is likewise held in a bearing recess 43b of the housing 43, the inner race of the bearing 44 being disposed in a recess 45a of a retainer member 45 which is screwed onto the housing 28 and locked thereon by a locknut 46. With this arrangement, the housing 28 is rotatable on bearings 44 and 42 in the bearing housing 43.

A quick-change lock 47, identical to the lock 31 previously described, is positioned in an outwardly extending cylindrical boss 43c of the housing 43. The plunger of this lock 47 is adapted to move into an indentation 28e of the housing 28 and thus lock the housing 28 on the bearing housing 43 which is an integral part of the chassis 10 through support member 19.

Steering by use of the feet is accomplished by means of a pair of foot pedals 48 and 48a which are rigidly attached on steering bars 49 and 49a respectively to the housing 28 (Figure 2). These bars are integral parts of the housing 28 extending outwardly from directly opposite sides of the main housing portion. On the outer end of each of these bars there is an upright peg 49b over which a support tube 50 is adapted to be positioned for pivoting movement thereon. Each foot pedal 48 and 48a is pivotally mounted on the tube 50 by means of a hinge 51, as best seen in Figure 1. Extending downwardly from the under surface of each foot pedal near the forward end thereof is a flange 52. For the purpose of adjusting the foot pedals in various tilting positions, a lever 53 is provided which is pivotally connected at one end to the lower end of the support post 50. At the opposite end the lever 53 takes the form of an open box 53a through which an adjusting screw 54, which is threaded into the flange 52, is positioned. When the screw 54 is backed off, the foot pedal may be pivoted on the hinge 51 and the box head 53a of the lever 53 will slide back or forth in relation to the adjusting screw 54 as desired. When the correct tilted position of the foot pedal is attained, the adjusting screw is brought down tightly on the box end 53a thus holding the pedal in that position.

Each foot pedal has an upwardly extending ridge 48b at the rear and a pair of upwardly extending pegs 48c disposed at the forward portion of the pedal. The ridge 48b is adapted to receive therein the heel of the occupant's foot and the pegs 48c are designed to prevent the forward part of the foot from sliding off the pedal.

It is now apparent that, when the quick-change lock 31 has been put in position to lock the housing 28 to the steering shaft 24 and the lock 47 has been withdrawn so that the housing 28 is free to rotate relative to the frame, the wheels may be steered by pushing on the foot pedals, since the pedals are secured to the housing 28 and the wheels are attached to the shaft 24.

It is desirable that the foot pedals be capable of assuming any pivoted position of the foot as the wheels are steered by the foot pedals. Usually the occupant of the chair will want to keep his feet directly forward as he pivots the steering bars 49 and 49a. This is possible in my in-

vention since the support posts 50 are pivotally mounted on the upright pegs 49b of the steering bars 49 and 49a. I have further provided a pair of coil springs 54a and 54b which are secured at one end to the housing 28 and at the other end to support posts 50. As a foot pedal is pushed forward and the straight ahead position of the pedal is maintained, the spring will be slightly elongated. Then when the foot is removed from the pedal the spring 54a or 54b will return the pedal to a position perpendicular to the steering bars 49. Usually when a person gets into this chair he will have positioned the steering wheels pointing straight forward and therefore the foot pedals will always be in a correspondingly straight forward position.

It is to be noted that if the lock 31 is pulled out so as to disconnect the housing 28 from the shaft 24 and the lock 47 is likewise pulled out to disconnect the housing 28 from the frame, the occupant can freely operate the steering wheels without affecting any steering of the wheels therewith. In this way a patient may effectively exercise his feet and legs while confined to the chair.

It is further to be noted that when it is desired that the vehicle be steered by other means, as by the movement of his back, which will be explained hereinafter, or by an attendant who is pushing the chair, the lock 31 is withdrawn so that the shaft 24 is free to rotate in the housing 28. Then if the lock 47 is put into position locking the housing 28 to the frame, the steering bars 49 and 49a are locked in position and the occupant then has a rigid support for his feet.

The seat assembly 55 comprises an upholstered seat 56 suitably secured to a fabricated support frame including four vertical angle members 57 disposed substantially beneath the four corners of the seat 56. Two upper side braces 57a and two lower side braces 57b connect the side vertical members 57, while an upper front brace 59, and a lower rear brace 59a and an upper rear brace 59b are disposed between the rear vertical members 57. These braces and members are suitably fastened together, as by welding, to form a rigid structure. The four vertical members 57 preferably have a square cross section. Near the lower end of each member a cylindrical passageway is provided in which is journaled a pair of longitudinal rods 60 and 60a. The rods 60 and 60a are rigidly fastened at each end in the frame cross members 12a and 12c, also passing through the member 12b. The seat and the seat frame are supported by these rods and may be slid back and forth thereon.

The seat assembly 55 also has a rear, centrally disposed frame member 61 which is secured by a flange portion 61a to the under surface of the seat by means of suitable screws 62. Near the lower end of member 61 a threaded passageway 61b is adapted to receive a threaded rod 63. The rod 63 is journaled in the cross brace 12c and is held against axial movement away from the brace 12c by a shaft collar 64 secured to the rod 63 immediately in front of the cross brace 12c by a setscrew 65 and by a crank 66 which is secured to the rod 63 immediately behind the cross brace 12c by a setscrew 67. Thus, when the rod 63 is turned by means of the crank 66 the member 61, in which the rod is threaded will be moved backwardly or forwardly as desired thus moving the entire seat assembly 55 along the longitudinal rods 60 and 60a. A stop nut 68 is disposed near

the end of rod 63 to limit the forward adjustment of the seat assembly.

An arm-rest assembly 70, provided at either side of the chair, includes an upholstered horizontal arm portion 71 secured to the upper end of a vertical rod 72a by means of a socket plate 73 and secured to the upper end of an inclined rod 72b by means of a socket plate 74. The lower terminal ends of the associated rods 72a and 72b are affixed together and each of the vertical rods 72a is slidably disposed in a support tube 75. The support tubes 75 are supported from the side braces 57 by means of support members 57b and 57c. Each vertical rod 72a may be adjustably positioned in the associated tube 75 by means of an adjustable screw 76. Thus each arm-rest 70 may be adjusted to any height to support an injured arm or it may be lowered completely to present easy ingress to the chair. As a support for the occupant's back and as a means for steering the chair by use of the occupant's back, I have provided a back assembly 80. This back assembly 80 includes two vertical rod members 81 and 82 secured in longitudinal alignment by cross braces 83. These rods are disposed substantially in a vertical direction. At its lower end the rod 81 is bent at right angles and projects forwardly into a cylindrical boss member 61c of the seat frame member 61. The rod is journaled in boss 61a passing therethrough to receive, immediately forward of the boss 61a a crank 84 which is keyed thereon.

As best seen in Figures 2 and 4, the crank 84 is pivotally secured to a lever 85 which in turn is pivotally connected to a crank lever 86. At its upper end the lever 86 is disposed about a drive shaft 87 which is keyed at its forward end to a bevel gear 88 in mesh with the bevel gear 25 on the front wheel steering shaft 24. At assembly the lever 86 is secured, as by brazing, to a sleeve member 89 whose forward portion is journaled in a cylindrical opening in the seat frame member 61. The enlarged rear portion of sleeve 89 contains a setscrew 90 by which the sleeve 89 and consequently the lever 86 is keyed to the shaft 87. In normal operation the sleeve 89 is keyed to the shaft and thus when the back support member 81 is pivoted from side to side in the bearing surface of member 61c, the crank 84 and the lever 85 will oscillate the lever 86 in a limited angular travel. Since the sleeve 89 and the lever 86 is secured to the drive shaft 87 by the setscrew 90, the shaft 87 will be rotated, thus operating the bevel gear front wheel steering mechanism. Thus I have provided a means for steering the chair by use of the occupant's back, an arrangement particularly useful to an invalid whose legs are injured or missing.

If it is desired to adjust the seat backward or forward on the rods 60 and 60a, the setscrew 90 is backed out and the adjustment is made by means of the crank 66. Thus the lower end of member 61 which abuts the sleeve 89 on one side and the lever 86 on the other, will move the back assembly and the seat assembly back and forth with it. Disposed about rod 81 just before the rod enters the boss 61c, is a substantially cylindrical member 91 which is keyed or pressed onto the rod 81. Forward and backward movement of the member 61a will also be transmitted to the back support assembly 80 through the abutting action of member 61a on this member 91 and on the crank 84.

An upper back rest 93 is slidably mounted on the upper end of the support rods 81 and 82, by

means of a tubular fitting 94 which is positioned over rod 82 and a lower tubular fitting 94a, secured to the lower end of fitting 94, which is adapted to be positioned about the rod 81. A flange 94b of the fitting 94 is suitably secured to the back rest 93 by screws 95. The purpose of the two tubular fittings 94 and 94a disposed about rods 81 and 82 is to prevent the back rest from becoming cocked to one side. The back rest 93 may be adjusted in a vertical direction by use of a setscrew 96 which is adapted to lock fitting 94 on the rod 82.

In order to most conveniently transmit the swaying movement of the occupant to the back rest 93 for steering purposes, I have provided two steering arms 97 and 97a which extend forwardly from the sides of the back rest 93 and are adapted to hug the occupant's body immediately below either armpit. As illustrated in Figures 1 and 5, a plate 98 is secured by a plurality of screws to the back of the back rest 93. Tubular members 99 and 99a, welded to the plate 98 receive lateral support arms 100 and 100a, which may be adjusted therein by use of setscrews 101. At their outer ends the lateral support arms have a passageway in which the forwardly extending steering arms 97 and 97a are held. These arms, 97 and 97a, may be adjusted back and forth in support arms 100 and 100a respectively by means of the setscrew 103. At the forward end of each arm is secured an oval shaped upholstered pad 104 which fits close to the occupant's body. Hence the swaying movement of the occupant's body may be efficiently transmitted to the back steering mechanism.

In instances where steering by the back is not required, it is desirable that the back support be rigidly held in a vertical position. In this invention this condition is provided for by means of a quick-change lock 105 disposed in a lateral arm 91a (Figures 7 and 8) of the cylindrical member 61, which is secured to the horizontal portion of rod 81. When the back steering mechanism is being used, the arm 91a oscillates between two limit screws 106 and 107 which are adjustably centered into overhanging arms 61d of the boss 61c which is part of the seat frame structure. The quick-change lock 105 is adapted to be secured at the outer end of the arm 91a, as shown in Figures 7 and 8. When the lock is in the withdrawn position, the arm 91a is free to oscillate between the limit screws 106 and 107, but when the lock is thrown into the locked position, as in Figure 8, the plunger of the lock fits into an opening in the boss 61c and thus locks the back steering mechanism to the frame.

Propulsion of this ambulatory chair may be effected by an attendant who controls the chair by means of the handle 13 or by the occupant who effects propulsion of the chair through a pair of levers 110 and 110a, one lever being disposed on either side of the chair. Near its lower end the lever 110 is pivoted on the upwardly extending ear 11b of the support member 11 (Fig. 1) by means of a shaft 112 which is journaled in both the ear 11b and a bushing member 110a of the lever 110. At its extreme lower end the lever 110 is pivotally connected to a rod 113 which is mounted for pivoting on a rod 114. A pair of crank arms 115 (Fig. 3) are also pivotable on the pin 114, one being connected at its other end to a crankshaft 116, and the other being connected at its other end to a shaft 116a aligned with shaft 116. The crankshaft is journaled in

a support member 117 depending from the frame member 11.

Lever 110a is connected to a crank mechanism in exactly the same way except that the crank arms 115 associated with the lever 110 lead the crank arms 115a which cooperate with the lever 110a by approximately 90°. All cranks are, of course, rigidly secured, as by a key, to the same crankshaft 116 which is supported in the downwardly depending support members 117 and 117a.

To transmit the rotation of the crankshaft to the rear wheels for driving thereof, there is supplied a sprocket and chain drive 120, best seen in Figure 4. The drive sprocket 121 is keyed for rotation with the crankshaft 116 while the sprocket 122, which is driven through a chain 123, rides free on the rear axle 15. When the chair is to be propelled by the occupant, the driven sprocket 122 is put into driving engagement with the rear axle 15 by means of a quick-change lock 124 secured to the axle at a point adjacent the sprocket 122. The plunger of lock 124 is adapted to engage in a hole 122a of the sprocket 122, as seen in Figure 9.

It is apparent that, if the occupant wishes to exercise his arms, without propelling the chair, disconnecting the lock 124 will allow him to work the levers 110 and 110a for this purpose.

By means of this apparatus, occupants having two arms may conveniently and, with a minimum of effort, propel the chair by working the levers 110 and 110a and thus rotating the crankshaft 116. The inner crank arm 115 is disposed on the crankshaft 116 approximately 90° ahead of the crank arm 115a in order that the chair will never stop on an immovable deadcenter position. If one crank did stop on deadcenter, the other would be in a position for moving the chair.

If the occupant has only one arm, only the lever on the side convenient to that arm is furnished. The lever on the opposite side may be efficiently eliminated since the crank arms, although keyed onto the crankshaft 116, may be easily removed or not furnished, being removably disposed on shafts 114 and 116 by suitable means, as by a key and cotter pins, or by a press fit. In this case, the unoccupied end of the crankshaft would be journaled in the support bushing 117, or 117a, and held against axial movement by some suitable means such as a washer and a large cotter pin.

To eliminate the possibility that the chair will stop on deadcenter when a one-armed occupant is propelling it, there is provided a short arm 125 which may be mounted alongside the longer arm 110. This short arm 125 is pivotally mounted on the rod 112 at a boss section 125a. At its lower end the lever 125 is pivotally secured to a rod 126 which in turn is pivotally connected to a crank arm 127, keyed to crankshaft 116. The crank arm 115, associated with the long lever 110, leads the crank arm 127 by 90°. Therefore, at any point at which the chair comes to rest, either the short arm or the long arm will be in a position to move the chair.

It is to be understood that, if the intended occupant has two arms, it is desirable that only the longer levers be furnished. If the person has only one arm, a short and long lever should be furnished on one side only. Since all crank arms are keyed on their respective shafts, any combination of lever arms may be furnished without also furnishing unnecessary mechanisms.

A further feature of the construction of the lever arms 110 and 110a is the provision of an

upper tubular section 110b of each arm which is adapted to telescope into a lower enlarged tubular section 110c. This feature permits the levers to be removed and thus provides, when the arm rest 70 has been lowered, a completely unobstructed opening through which an invalid patient may be placed in the chair. An adjusting screw 120a threaded into section 110c is provided to hold the lever 110 or 110a in any desired raised position.

To prevent the chair from moving when a person is getting into or leaving it, I have provided a brake mechanism 130 which, as illustrated in Figure 4, comprises a brake lever 131 having a knob 132 disposed within easy reach of an occupant of the chair. The lever 130 is pivoted on a pin 133 secured in the frame member 19e. A tubular member 134, pivotally mounted on a pin 135 disposed in the lever 131, is adapted to receive therethrough a push rod 136 which carries a shoulder portion 136a. Disposed about the rod 136 between the shoulder 136a and the tubular member 134 is a coil spring 137. At the end opposite to the brake lever end, the rod 136 is pivotally disposed about a brake rod 138, which is journaled near its ends in downwardly extending arms 139 and 139a pivotally secured to the frame members 11 and 11a.

When the brake lever 131 is rotated counterclockwise about the pin 133, the tubular member pivotally secured on pin 135 moves through a comparatively flat arc about the pin 133 at center. The spring 137 is compressed thus pushing the shoulder 136a, and consequently the rod 136, rearwardly. The brake rod 138 is thus pressed into braking engagement with the rear wheels. When the rod 138, the pin 135 and the pin 133 are in line, the brake mechanism is on dead center. As the lever arm 131 is pivoted further, the pin 135 is swung over dead center into a locked position. The spring 137 now acts to hold the lever in this position. The knob 132 is, of course, within easy reach of the occupant of the chair, even in the locked position.

From the foregoing it is evident that there is provided in this invention a novel type of ambulatory chair that is adapted for use, not only by persons who are recovering from illness, but also by those who are incapacitated, even to the extent of having lost both their legs and an arm.

It will, of course, be understood that various details of construction may be varied throughout a wide range without departing from the principles of this invention, and it is, therefore, not the purpose to limit the patent granted hereon otherwise than necessitated by the scope of the appended claims.

I claim as my invention:

1. An ambulatory chair comprising a pair of rear wheels, a pair of steering wheels disposed forwardly from said rear wheels, a first axle journaled in said rear wheels, a second axle journaled in said steering wheels, a slidably adjustable frame structure, means supporting said frame structure on said first and second axles including a steering yoke member through which the second axle extends, the yoke member being pivoted on the frame structure for movement about a generally vertical axis, a steering assembly responsive to the movements of the occupant's back, said steering assembly comprising an upright arm pivotally supported in said frame structure, a crank mechanism actuated by said arm, a drive shaft disposed for rotation by said crank mechanism, a first gear secured to said

shaft, a second gear enmeshed with said first gear and secured to said steering yoke member for rotating of said front wheels about the generally vertical pivotal axis of the yoke member.

2. An ambulatory chair comprising a support structure, front and rear wheels supporting said structure, a shaft secured to said front wheels and journaled in said structure affording a vertical pivot axis for said front wheels, a rod journaled on said support structure and in driving engagement with said shaft, a seat assembly slidably mounted on said structure for adjustment longitudinally thereof, an oscillatable mechanism having a crank arm adjustably slidable on said rod and normally keyed to the rod for oscillating the rod to effect oscillation of said shaft, and guide members pivotally mounted on said structure and arranged to fit closely on either side of the body of the occupant of said seat and connected to said arm, said crank arm being adjustable longitudinally of the support structure by abutting contact of said seat assembly upon adjustment of the seat assembly.

3. An ambulatory chair comprising a rigid support structure, front and rear wheels supporting said structure, a shaft secured to said front wheels and journaled in said structure affording a vertical pivot axis for said front wheels, a rod journaled on said support structure and in driving engagement with said shaft, a seat assembly slidably mounted on said structure having an upright support member disposed intermediate the side edges of said seat assembly and depending therefrom, an oscillatable mechanism mounted on said seat assembly and including a crank arm slidably adjustable on said rod and normally keyed thereto, and collars on said crank arm on either side of said depending support member, said crank arm being slidable on said shaft by abutting contact of said member with one of said collars as said seat is adjusted.

4. An ambulatory chair comprising a support structure, front and rear wheels supporting said structure, a shaft secured to said front wheels and journaled in said structure affording a vertical pivot axis for said front wheels, a rod journaled on said support structure and in driving engagement with said shaft, a seat assembly mounted on said structure, an oscillatable arm connected to said rod for oscillating the same to effect oscillation of said shaft, guide members arranged to fit closely on either side of the body of the occupant

of said seat and connected to said arm, and means for limiting the range of oscillating movement of said arm.

5. An ambulatory chair comprising a support structure, front and rear wheels supporting said structure, a shaft secured to said front wheels and journaled in said structure affording a vertical pivot axis for said front wheels, a rod journaled for rotation longitudinally of said support structure, a seat assembly slidably adjustable on said structure, an oscillatable crank mechanism connected to said rod and having a portion journaled for oscillation in said seat assembly and secured against longitudinal movement relative to said seat assembly, an arm extending transversely of said portion adjacent said seat assembly, and an abutment arm secured to said seat assembly and projecting outwardly on either side of said arm to limit the range of oscillation of said arm.

6. In an ambulatory chair of the type wherein a frame structure is mounted on rear wheels and steerable front wheels, the improvement which comprises a generally vertical steering shaft connected to said front wheels and journaled in the frame structure for rotation about its generally vertical axis, foot actuated levers, locking means for connecting said levers to said shaft for rotating the same, an oscillatable back rest, a lever mechanism connecting said back rest to said shaft to cause oscillation of said shaft when said locking means is disengaged.

WALTER R. NELSON.
